UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

BINDER DEVICE.

1,202,345.

Specification of Letters Patent.

Patented Oct. 24, 1916.

Application filed November 27, 1915. Serial No. 63,742.

To all whom it may concern:

Be it known that I, GEORGE P. WIGGINTON, a citizen of the United States, residing at Kalamazoo, county of Kalamazoo, State 5 of Michigan, have invented certain new and useful Improvements in Binder Devices, of which the following is a specification.

This invention relates to improvements in binder devices.

10 My present improvements are especially designed by me for use with temporary binders or loose sheet holders such as illustrated and described in my application for Letters Patent, filed March 19, 1915, Ser. 15 No. 15,590. My present improvements are, however, adapted and desirable for use with various types of temporary binders having separably associated binder members which may be separated to facilitate the insertion 20 and removal of sheets.

The main objects of this invention are: First, to provide an improved binder device which facilitates the use of temporary binders or loose sheet holders. Second, to 25 provide an improved device which is capable of being adjusted to position to receive a binder and to the desired position to support and facilitate the handling of the sheets.

30 Further objects, and objects relating to structural details, will definitely appear from the detailed description to follow.

I accomplish the objects of my invention by the devices and means described in the 35 following specification.

The invention is clearly defined and pointed out in the claims.

A structure which is a preferred embodiment of my invention is clearly illustrated 40 in the accompanying drawing, forming a part of this specification, in which:

Figure I is a side view of a structure embodying the features of my invention with a temporary binder arranged therein. Fig. 45 II is a plan view, partially in section, on a line corresponding to the broken line 2—2 of Fig. I. Fig. III is a vertical longitudinal section on a line corresponding to the broken line 3—3 of Fig. II, with the parts in ex-

50 tended position. Fig. IV is a detail side elevation of a slightly modified structure in which the base is non-adjustable.

In the drawing similar reference characters refer to similar parts throughout the 55 several views, and the sectional views are

taken looking in the direction of the little arrows at the ends of the section lines.

Referring to the drawing, the binder, which is illustrated in order to better show the manner of using my improvements, comprises a pair of covers 1 and 2, which are provided with chambers adapted to receive the adjusting mechanism. Binding strips 3 extend between and into the covers and are connected to the adjusting mechanism. The 60 adjusting mechanism shown is that of U. S. Letters Patent to Bushong, No. 878,340, Feb. 4, 1908, and comprises a screw mechanism 4 in one cover and ratchet mechanism 5 in the other. I preferably provide clamping bars 6 which are pivotally connected to the covers. The clamping bars are preferably provided with post sockets, such as applicant describes in his said application, in which application the manner of use is 65 described in detail as is also the manner of manipulating the sheets or leaves 7. These sheets have uniformly spaced open slots or notches 8 at their inner edges and closed 70 holes 9 uniformly spaced relative to each other and relative to the notches.

I provide a pair of holders each adapted to receive one of the binder members comprising, in the structure illustrated, a cover and its clamping member. Each holder 85 comprises a side member 10 and an end member 11. The holders are supported on a base which, in the structure shown in Figs. I and III, comprises a pair of members 12 associated for adjustment to and from each other. The base members are connected and secured in their adjusted positions by slotted arms 13 secured to one member at 14 and adjustably secured to the other by means of the bolts and thumb nuts 15. Each base 90 member consists of a pair of side members connected by cross pieces 16. The base members are provided with upright portions 17 at their outer ends.

The holders are disposed oppositely with 100 their end members adjacent and pivotally connected to each other by hinges 18 and to their respective side members by the hinges 19.

In the structure illustrated in Figs. I-III 105 the holders are pivotally secured to the base members at 20. The side members of the holders are further adjustably supported by means of the notched links 21, which are pivotally connected to the side members at 110

22 and adjustably engaged with the studs 23. With the parts thus arranged, the holders may be adjusted with their end members in a horizontal position or in 5 alinement, as shown in Fig. III, or to an oppositely inclined relation, as shown in Figs. I and II. The end members are provided with registering slots 24 adapted to receive the binding strips when the end 10 members are erected. The separating movement of the base members collapses the holder end members and their closing movement swings them to their erected position. The side members of the holders may be 15 adjusted to any position within their scope of adjustment.

In the modification shown in Fig. IV my improvements are shown embodied in a structure having a non-adjustable base and 20 in that structure the holders are not pivotally connected to the base. The holders are supported in their erected position by the latch 25 pivotally mounted on one end member and notched to engage the pin 26 on the other.

I preferably provide the end members of 30 the holders with guides 27 with which the notches of the sheets may be engaged to associate in alining the sheets with the binding strips.

My improved binder device greatly facilitates the use of temporary binders where it is desired to frequently remove or insert sheets, such as, for instance, is the case 35 where the records are kept on a typewriting machine. The sheets are supported so that they are readily accessible and the wear thereon is minimized.

I have illustrated and described my 40 improvements in two embodiments. I have not attempted to illustrate or describe all the embodiments which I contemplate as I believe the disclosure made will enable those skilled in the art to which my invention 45 relates to embody or adapt the same to the particular style of binder for which they are designed to support. I desire, however, to be understood as claiming my improvements specifically in the form illustrated 50 as well as broadly within the scope of the appended claims.

Having thus described my invention, what I claim as new and desire to secure by Letters Patent, is:

55 1. In a support for temporary binders comprising a pair of separably associated binder members and binding strips extending between said members, the combination of a pair of base members associated for 60 adjustment to and from each other and having horizontal portions with uprights at their outer ends, means for securing said base members in their adjusted positions, a pair of holders comprising end members and side members disposed oppositely with their end

members pivotally connected to each other and to their respective side members so that they may be collapsed into alinement upon the base or erected to an oppositely inclined position, supporting links pivotally connected to said side members, and adjustably connected to said base uprights, said end members having registering slots adapted to receive said binding strips when the end members are erected. 70

2. In a support for temporary binders comprising a pair of separably associated binder members and binding strips extending between said members, the combination of a base, a pair of holders comprising end members and side members disposed oppositely with their end members pivotally connected to each other and to their respective side members so that they may be collapsed into alinement upon the base or erected to 80 an oppositely inclined position, toothed supporting links pivotally connected to said side members, and studs on said base uprights with which said links are adjustably engaged, said end members having registering slots adapted to receive said binding strips when the end members are erected. 85

3. In a support for temporary binders, comprising a pair of separably associated binder members and binding strips extending between said members, the combination of a base, a pair of holders comprising end members and side members disposed oppositely with their end members pivotally connected to each other and to their respective 90 side members, so that they may be collapsed into alinement upon the base or erected to an oppositely inclined position, supporting links pivotally connected to said side members and adjustably connected to said base, said end members having registering slots adapted to receive said binding strips when the end members are erected. 95

4. In a support for temporary binders comprising a pair of separably associated binder members and binding strips extending between said members, the combination of a pair of base members associated for adjustment to and from each other, means for securing said base members in their adjusted positions, a pair of holders comprising end members and side members disposed oppositely with their end members pivotally connected to each other and to their respective side members so that they may be collapsed or erected to an oppositely inclined position, said side members being pivotally and adjustably supported on said base, said end members having registering slots adapted to receive said binding strips when the 100 end members are erected. 110

5. In a support for temporary binders comprising a pair of separably associated binder members and binding strips extending between said members, the combination 115

- of a pair of holders comprising end members and side members disposed oppositely with their end members pivotally connected to each other and to their respective side members so that they may be collapsed or erected to an oppositely inclined position, said side members being pivotally and adjustably supported on said base, said end members having registering slots adapted to receive 5 said binding strips when the end members are erected.
6. In a support for temporary binders comprising a pair of separably associated binder members and binding strips extending between said members, the combination of a pair of base members associated for adjustment to and from each other, a pair of holders comprising end members and side members disposed oppositely with their end 10 members adjustably associated relative to each other and relative to their respective side members so that they may be collapsed into alinement or erected to an oppositely inclined position, said side members being pivotally and adjustably supported on said base, said end members having registering slots adapted to receive said binding strips when the end members are erected.
7. In a support for temporary binders comprising a pair of separably associated binder members and binding strips extending between said members, the combination of a pair of holders comprising end members and side members disposed oppositely 15 with their end members adjustably associated relative to each other and relative to their respective side members so that they may be collapsed into alinement or erected to an oppositely inclined position, said side members being pivotally and adjustably supported on said base, said end members having registering slots adapted to receive said binding strips when the end members are erected.
8. In a support for temporary binders comprising a pair of separably associated binder members and binding strips extending between said members, the combination of a pair of holders comprising end members and side members disposed oppositely 20 with their end members adjustably associated relative to each other and relative to their respective side members so that they may be collapsed or erected to an oppositely inclined position, said side members being pivotally and adjustably supported on said base, said end members having registering slots adapted to receive said binding strips when the end members are erected.
9. In a support for temporary binders, the combination of a pair of base members associated for adjustment to and from each other and having horizontal portions with uprights at their outer ends, means for securing said base members in their adjusted 25 positions, a pair of holders comprising end members and side members disposed oppositely with their end members pivotally connected to each other and to their respective side members so that they may be collapsed into alinement upon the base or erected to an oppositely inclined position, supporting links pivotally connected to said side members and adjustably connected to said base uprights.
10. In a support for temporary binders, the combination of a base, a pair of holders comprising end members and side members disposed oppositely with their end members pivotally connected to each other and to their respective side members so that they may be collapsed into alinement upon the base or erected to an oppositely inclined position, toothed supporting links pivotally connected to said side members and studs on said base uprights with which said links are adjustably engaged.
11. In a support for temporary binders, the combination of a base, a pair of holders comprising end members and side members disposed oppositely with their end members pivotally connected to each other and to their respective side members so that they may be collapsed into alinement upon the base or erected to an oppositely inclined position, supporting links pivotally connected to said side members and adjustably connected to said base.
12. In a support for temporary binders, the combination of a pair of base members associated for adjustment to and from each other, means for securing said base members in their adjusted positions, a pair of holders comprising end members and side members disposed oppositely with their end members pivotally connected to each other and to their respective side members so that they may be collapsed or erected to an oppositely inclined position, said side members being pivotally and adjustably supported on said base.
13. In a support for temporary binders, the combination of a pair of holders comprising end members and side members disposed oppositely with their end members pivotally connected to each other and to their respective side members so that they may be collapsed or erected to an oppositely inclined position, said side members being pivotally and adjustably supported on said base.
14. In a support for temporary binders, the combination of a pair of base members associated for adjustment to and from each other, a pair of holders comprising end members and side members disposed oppositely with their end members adjustably associated relative to each other and relative to their respective side members so that they may be collapsed into alinement or erected to an oppositely inclined position,

said side members being pivotally and adjustably supported on said base.

15. In a support for temporary binders, the combination of a pair of holders comprising end members and side members disposed oppositely with their end members adjustably associated relative to each other and relative to their respective side members so that they may be collapsed into alinement or erected to an oppositely inclined position, said side members being pivotally and adjustably supported on said base.

16. In a support for temporary binders, the combination of a pair of holders comprising end members and side members disposed oppositely with their end members adjustably associated relative to each other and relative to their respective side members so that they may be collapsed or erected to an oppositely inclined position.

17. In a support for temporary binders, the combination of a pair of base members associated for adjustment to and from each other, a pair of holders comprising end members and side members disposed oppositely with their end members pivotally connected to each other and to their respective side members, said end members being also pivotally connected to said base members so that when the base members are extended the end members are collapsed and when the base members are retracted the end members are erected, and means for adjustably supporting said side members on said base members.

18. In a support for temporary binders, the combination of a pair of base members associated for adjustment to and from each other, a pair of holders comprising end members and side members disposed oppositely with their end members pivotally connected to each other and to their respective side members, said end members being also pivotally connected to said base members so that when the base members are extended the end members are collapsed and when the base members are retracted the end members are erected, and means for securing said base members in their adjusted positions.

19. In a support for temporary binders, the combination of a pair of base members associated for adjustment to and from each other, a pair of holders comprising end members and side members disposed oppositely with their end members pivotally connected to each other and to their respective side members, one holder being pivotally connected to each base member so that when the base members are extended the end members are collapsed and when the base members are retracted the end members are erected, and means for adjustably supporting said side members on said base members.

In witness whereof, I have hereunto set my hand and seal in the presence of two witnesses.

GEORGE P. WIGGINTON. [L. S.]
